DIAPER COVER

Lucy Warinner, Portland, Oreg.

Application January 2, 1934, Serial No. 704,844

2 Claims. (Cl. 128—284)

My invention relates to infant's moistureproof diaper-cover.

In the construction of diaper-covers at present in general use, as known to me, the arrangement of certain parts is such as to overlap, and thus produce double thicknesses of material, tending to bind the infant, restricting circulation and chafing the skin.

The object of my invention is to provide a more comfortable and hygienic moistureproof diaper-cover, easily put on the infant, comfortable to wear, not irritating or chafing the skin, nor interfering with free circulation; nor overheating, which is one of the principal causes of chafing, since it renders the skin very sensitive and easily irritated; also to make my diaper cover self-supporting, that is, not requiring safety pins for securing it in place on the infant.

I attain the object of my invention by a diaper-cover made of a single sheet of material, having no avoidable overlapping parts, and secured in place without safety pins or straps; my diaper-cover being made as illustrated in the accompany drawing, and hereinafter described.

25 In the drawing:

Fig. 1 shows the back or outer side of a sheet of material shaped to make my diaper-cover; the edges of the sheet being bound but the sheet not yet finished into my diaper-cover;

30 Fig. 2 shows a front, or inner side view of my diaper-cover finished;

Fig. 3 illustrates the placing of my diaper-cover on an infant;

Fig. 4 illustrates the diaper-cover as put on; 35 and

30 Figs. 5 and 6 illustrate details of construction; Fig. 5 showing an inside view of a corner of the upper end of my diaper-cover; and Fig. 6 showing the back or outer side of a corner of the upper end of my diaper-cover.

My diaper-cover comprises a sheet *a* made of moisture proof material, preferably light rubber fabric, and cut to pattern as shown by Fig. 1.

As will be noted, the sheet is widest at the upper end *a'*, and narrowest at the lower end *a2*. The intermediate lateral portions are cut to form receding concave portions as at *a2*; and these portions are adapted to provide loose fitting leg openings when my diaper-cover is put on the infant. The receding side portions *a2* are connected with the side portions *a'* by obliquely cut, upwardly tapering portions *a3*, the two portions *a', a2* forming angular side portions with each other; and the lower end *a4* is connected with the

receding portions *a2* by convex and downwardly tapering portions *a5*, Fig. 1.

The upper and lower ends *a', a4* of my diaper-cover have sewed on their inner faces tapes *b, b'* fastened by stitches *c, c'* at their edges, so as to constitute guideways in each of which is inserted a rubber band *d*, whose ends are secured by stitches *e*, as illustrated in Fig. 5. The ends *b3* of the tapes *b, b'* provide reinforcements of the sheet *a*, on which are sewed taped rubber buttons *f, f'*, as illustrated by Fig. 6.

Below the tape *b* at the upper end of my diaper-cover the sheet *a* is reinforced at the sides by tapes *g, g'* on which are sewed taped rubber buttons *h, h'*.

Two buttons *f, f'* and *h, h'* are provided so that the diaper-cover may be properly placed on infants of different sizes.

The edge of the sheet *a* is bound all around by a tape *i* as illustrated. The lower end portions *a4* of my diaper-cover are reinforced by tapes at *j, j'* in which are formed button holes *k, k'* to be engaged by one of the buttons *h, h'*. The tape *b'* of the lowermost end of my diaper-cover has also formed at its ends button holes *l, l'* to be 25 engaged with one of the buttons *f, f'*.

The rubber bands *d* are arranged to draw the upper and lower ends of my diaper-cover together crosswise, as illustrated by *m* and *m'*; in that way holding the diaper-cover firmly but 30 comfortably in place on the infant, without safety pins.

My diaper-cover is put on the infant by lapping forward the upper lateral portions *a'* so as to arrange the same as illustrated at *a6* in Fig. 3. 35 The lower portion *a4* of my diaper-cover is then brought up and secured in place by the buttons *f* or *f'* and *h* or *h'*, the diaper-cover thus becoming arranged as illustrated by Fig. 4.

It will be noted that the upper and lower end 40 side portions of my diaper-cover are adapted to have only a narrow overlap when fastened together and thus leave only a single thickness between said overlapped portions, in that way assuring that the infant's body will not be overheated by my diaper-cover and thus subjected to 45 discomforts and cause irritation as mentioned.

It is further to be noted that the cut of the intermediate side portions *a2* of the sheet *a* is such as to provide ample fullness for the legs of the 50 infant when the diaper-cover is put on, as illustrated by dotted lines in Fig. 4; thus giving the infant's legs ample room, and preventing any binding and insuring circulation of air under the diaper-cover.

I claim:

1. A one-piece diaper-cover having front and rear end portions of substantially rectangular shape with the front end portion of less width than the rear end portion, the intermediate portion of the cover having substantially V-shaped inwardly directed side edges with rounded apex, the distance between the apices of the side edges of the intermediate portion transversely of the cover being less than the similar dimension of the front end portion of the cover to provide leg openings and a crotch portion for the cover, strips secured on the inner surface of the cover adjacent each end thereof in transversely aligned pairs to provide pockets, elastic sections secured within the pockets of each pair and bridging the space of the cover between the pockets, the normal length of such elastic sections being less than the similar dimension of the portions of the cover with which they cooperate to thereby normally exert a drawing effect on the cover adjacent its ends, fastening elements secured to the outer surface of the cover and to and through the strips at such outer end to reinforce the fastening elements, means with which the fastening elements cooperate formed in the opposite end of the cover

and to and through the strips at that end to reinforce such means, and additional fastening elements formed on the respective end portions of the cover longitudinally spaced from the first mentioned fastening elements.

2. An adjustable diaper cover comprising a body section having front and rear portions adapted to be fastened together at the sides, the fastening means being arranged for connection in any of at least two positions to render the size of the diaper cover adjustable in application, the body section having longitudinal folds whereby such body section is laterally expansible, and rubber bands secured across the ends of the front and rear portions of the body section, normally holding the body section in its smallest width, the sides of said front and rear portions having narrow extensions adapted to be overlapped and secured by the fastening means, said overlapping sections being arranged so as to confine the overlapping to the sides of the body section of the diaper cover, whereby in any arrangement in size of the diaper cover any double thickness of that portion of the cover extending over the abdomen of the infant will be prevented.

LUCY WARINNER.
